UNITED STATES PATENT OFFICE

106,249

DESIGN FOR AN AUTOMOBILE RADIATOR ORNAMENT OR SIMILAR ARTICLE

Gustav Bohland, Miami Beach, Fla.

Application November 20, 1936, Serial No. 66,193

Term of patent 7 years

To all whom it may concern:

Be it known that I, Gustav Bohland, a citizen of Czechoslovakia, residing at Miami Beach, in the county of Dade and State of Florida, have invented a new, original, and ornamental Design for an Automobile Radiator Ornament or Similar Article, of which the following is a specification, reference being had to the accompanying drawing, forming part thereof.

Fig. 1 is a perspective view of one side of an

ornament according to my new design, the opposite side being similar in appearance.

Fig. 2 is a section taken in a horizontal plane about the middle of the pedestal on line II-II of Fig. 1 and looking downward therefrom.

I claim:

The ornamental design for an automobile radiator ornament or similar article, as shown and described.

GUSTAV BOHLAND.
